(57) **CLAIM**

The ornamental design for a drug screening instrument as shown and described.

DESCRIPTION

The patent or application file contains at least one drawing executed in color. Copies of this patent or patent application publication with color drawing(s) will be provided by the Office upon request and payment of the necessary fee.

1. Drug screening instrument

1.1 : Front

1.2 : Back

1.3 : Left

1.4 : Right

1.5 : Top

1.6 : Bottom

1.7 : Perspective

The product of the design is drug screening instrument, which is used for screening drugs. The main point of the design is the shape. Perspective view represents the main point of the design.

1 Claim, 7 Drawing Sheets
